UNITED STATES PATENT OFFICE

DESMOND WALTER MOLINS, OF LONGWOOD, BEXLEY, ENGLAND

CIGARETTE MACHINE

Application filed September 9, 1931. Serial No. 561,960.

This invention relates to apparatus for feeding tobacco and more particularly to feeding apparatus for use in cigarette making machines of the continuous rod type. The principal object of the invention is the provision of means for collecting and removing the dust produced in conveying and treating the shredded tobacco.

It has heretofore been proposed to remove this dust by suction producing means but it is found that such means are not entirely satisfactory since there is a tendency to withdraw a portion of the shredded tobacco together with the dust if the suction is applied sufficiently close to the shredded tobacco to become effective. Furthermore, it is frequently necessary to project the tobacco in an unsupported stream, for instance in discharging tobacco into the filling trough of a continuous rod type of cigarette machine, and the provision of suction devices for withdrawing the dust adjacent such a stream of falling tobacco tends to divert the stream from its proper course.

It is therefore an object of the invention to provide mechanical means rather than pneumatic devices for withdrawing dust generated during the feeding of the tobacco.

It is a further object of the invention to provide means for housing the tobacco conveying apparatus in such manner as to eliminate empty pockets or waste spaces in which dust may collect in sufficient quantity to fall into or mix with the shredded tobacco.

Further objects and features of the invention will be apparent from the following description taken in connection with the accompanying drawing in which:

Figure 1 is a fragmentary vertical section through tobacco feeding apparatus commonly used in cigarette making machines of the continuous rod type to which the invention has been applied;

Figure 2 is a plan view of the moving parts disclosed in Figure 1 with the housing removed; and

Figure 3 is a fragmentary sectional view on the line 3-3 of Figure 1.

Referring now specifically to the apparatus shown in the drawing which has been chosen

to illustrate the application of the principles of the invention, it will be observed that the reference numeral 10 designates the conventional carded drum on which the shredded tobacco is deposited and which serves to convey the tobacco to the usual filling trough of the cigarette making machine, not shown. This drum is rotated in the direction of the arrow and the tobacco carried thereon is pressed out in a uniform layer by the action of the comb 12 mounted in the comb bar 13 and engaging the tobacco between the rows of pins 14 on the carded drum 10.

A picker roller 16, provided with a plurality of series of radially projecting pins 17 on the periphery thereof, serves to remove the shredded tobacco from the drum 10 and discharge the same in a stream downwardly into the filling trough as shown in Figure 1 of the drawing, and as is well understood in the art. The pins 17 are preferably threaded in apertures 19 in the picker roller and are secured in position by lock nuts 20. The picker roller is preferably rotated in a direction opposite to the direction of rotation of the carded drum 10.

A mechanical conveyor for removing dust from the vicinity of the picker roller is provided, this conveyor preferably comprising a rotating roller 25. Ribs 26 are provided on the periphery of this roller, and the roller 25 and the picker roller 16 are disposed in such close proximity that these ribs pass between adjacent rows of pins on the picker roller as shown more clearly in Figure 3 of the drawing.

A suitable guiding wall or partition 27 is provided to separate the falling stream of tobacco from the dust discharged from the roller 25, this discharge of dust being effected by means of a series of fingers 28, preferably resilient, engaging between adjacent ribs 26 on the dust collecting roller. These fingers serve as scrapers and dust directed on and about the ribbed periphery of the roller 26 by the action of the picker roller is thus removed by the fingers 28 and discharged downwardly into a suitable receptacle.

By reason of the fact that dust adheres closely to surfaces located within and ad-

jacent the draft caused by the picker roller, the ribbed conveyor 25 is found to be extremely effective in extracting and removing this dust. At the same time the depositing 5 of dust on other surfaces adjacent the picker roller is prevented by the provision of a housing 30 conforming closely to the contour of the pins disposed about the periphery of this roller. A housing 29 is likewise provided 10 about the ribbed periphery of the roller 25, these housings forming shrouds to confine any dust within the machine and prevent the collection of appreciable quantities of dust in pockets or waste spaces in the housing which 15 might fall into the moving stream of tobacco.

It will be appreciated that while the invention is particularly applicable to the conventional type of cigarette machine employing a carded drum or conveyor and a picker roller for removing and discharging tobacco from the conveyor, it may be successfully used at other points in such machines or in any type of machine in which shredded tobacco is being conveyed or treated so as to release a considerable quantity of dust. It will 25 also be appreciated that the roller 25 may assume other forms, it being only necessary that a conveyor be provided with a dust collecting surface which is moved into and out of the zone in which dust is discharged by the moving parts of the machine. Such further changes and alterations are contemplated as fall within the spirit and scope of the appended claims.

Having thus described the invention, what is claimed as new and desired to be secured by Letters Patent is:

1. In apparatus for feeding tobacco, the combination with a carded conveyor for the 40 tobacco, of a picker roller having projections thereon for removing tobacco from said conveyor, and means moving between the projections on said roller for collecting and removing dust.

2. In apparatus for feeding tobacco, the combination with a carded conveyor for the tobacco, of a picker roller having projections thereon for removing tobacco from said conveyor, and a rotating element having a plurality of circumferentially extending ribs on the periphery thereof, said picker roller and said element being disposed in close proximity with the ribs on said element passing between the projections on said roller for collecting and conveying dust therefrom.

3. In a cigarette making machine of the continuous rod type having a filling trough through which tobacco is delivered to a traveling web of paper, the combination with a 60 carded conveyor for the tobacco, of a picker roller having pins thereon for removing tobacco from said conveyor for discharge into the filling trough, and a rotatable element having circumferentially extending ribs on the periphery thereof projecting between the

pins on the picker roller for collecting dust, and means for removing the dust from said element.

4. In a cigarette making machine of the continuous rod type having a filling trough through which tobacco is delivered to a traveling web of paper, the combination with a carded conveyor for the tobacco, of a picker roller having pins thereon for removing tobacco from said conveyor for discharge into the filling trough, and a rotatable element having circumferentially extending ribs on the periphery thereof projecting between the pins on the picker roller for collecting dust, and means for removing the dust from said element, and a housing comprising a shroud for said picker roller disposed in close proximity to the picker roller pins to prevent accumulation of appreciable quantities of dust on such portion of the interior of the housing.

5. In a cigarette making machine of the continuous rod type having a filling trough through which tobacco is delivered to a traveling web of paper, the combination with a carded conveyor for the tobacco, of a picker roller having pins thereon for removing tobacco from said conveyor for discharge into the filling trough, and a rotatable element having circumferentially extending ribs on the periphery thereof projecting between the pins on the picker roller for collecting dust, means for removing the dust from said element, and a housing conforming closely to the peripheral outlines of said picker roller and rotatable element for preventing accumulation of dust.

6. In a cigarette making machine of the continuous rod type having a filling trough through which tobacco is delivered to a traveling web of paper, the combination with a carded conveyor for the tobacco, of a picker roller having pins thereon for removing tobacco from said conveyor for discharge into the filling trough, and a rotatable element having circumferentially extending ribs on the periphery thereof projecting between the pins on the picker roller for collecting dust, and fixed means projecting between the ribs on said rotatable element to remove dust therefrom.

In testimony whereof I hereunto affix my signature.

DESMOND WALTER MOLINS.
